UNITED STATES PATENT OFFICE

2,469,576

HAIR CURLER

Saidee M. Ritter, Los Angeles, Calif., assignor of one-third to Ethel N. Haynor and two-thirds to Archie E. Coppleman, both of Los Angeles, Calif.

Application February 10, 1947, Serial No. 727,526

1 Claim. (Cl. 132—38)

1

This invention relates to hair curlers and more especially to curlers applied by the user rather than by a professional hair dresser.

An object of the invention is to provide a simple, practical and inexpensive hair curler of the character described.

Another object of the invention is to provide an improved hair curler incorporating simple clamping features such that the curler can be easily applied.

A further object of the invention is to provide a novel hair curler that is substantially flat and which may be retained in position without discomfort overnight or while sleeping.

Other objects and advantages will appear and be brought out more fully in the following specification considered with reference to the accompanying drawing throughout which like parts are designated by like numerals.

In the drawing:

Figure 1 is a perspective view showing my invention in use.

Figure 2 is an illustrate view showing a number of curlers of my invention in use.

Figure 3 is a face view of a preferred form of my invention.

Figure 4 is a view similar to Figure 3 showing a modified form of the invention.

Figure 5 is a side view of the invention of Figure 4 shown in closed position.

Referring more particularly to the drawing and especially to Figures 1 and 3, I show a preferred form of my invention comprising a wire 10 bent or formed into a pair of primary loops 11 and 12 and a secondary loop 13 and having end portions 14 and 15. Wire 10 is continuous, as shown, and a portion thereof, as at 16, is common to both loops 11 and 12, end portions 14 and 15 being wound around portion 16, forming small coils 17 constituting in effect a hinge or pivot construction together with portion 16, which is bendable.

A wire system 18, preferably of finer wire than wire 10, is strung or wound as by coils 19 to and across loops 11 and 12 and forms a framework providing a plurality of openings 20 and serves as a retainer for the curl of hair when held by the curler. Loop 13 is seen as being formed by wire 10 at one edge of loop 11 and at the opposite side from portion 16 and is adapted to be bent over and around loop 12 when in the curl holding position.

Figures 1 and 2 show the curler of Figure 3 in use. The curler is applied in open position, as shown in Figure 3, and a lock of hair is first wound into a curl, as at 21, and the curl placed between the elements comprising frames 11 and 12, one frame being bent over the other to compress or hold the curl 21 therebetween and loop 13 bent outwardly and around to hold frame loop 12 against and in clamping relation to frame loop 11.

2

11. The curler when in curl holding position, as shown in Figures 1 and 2, is substantially flat and a number of the curlers can be applied to the hair of the head, as shown in Figure 2, and will not be uncomfortable to the user, as when the user is resting or sleeping.

In Figures 4 and 5, I show a modified form of my invention. In these figures a pair of flat elements 25 and 26, which may be of any suitable, substantially rigid material, such as metal, plastic or the like, are hinged or pivoted together at 27 and each has an open framework 28. Member 25 is shown as having a clasp 29 for engaging the pin 30 or other complementary clamping element, whereby the members 25 and 26 may be held in detachable clamping position when holding a lock or curl of hair therebetween. The invention, according to Figures 4 and 5, functions substantially similarly to that of Figures 1 to 3, the action of hinge or pivot 27 being similar to that of the twist or bend afforded by portion 16 of wire 10.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claim so as to embrace any and all equivalent devices and systems.

Having thus described my invention, what I claim and desire to secure by Letters Patent is:

A hair curler, as described, comprising in combination a pair of substantially flat, net-like elements adapted to be arranged in overlapping position, and means for clamping said elements together with a lock of hair therebetween, said elements including a common wire frame adapted to be bent to permit positioning in overlapping arrangement.

SAIDEE M. RITTER.
